UNITED STATES PATENT OFFICE.

JAMES S. FAULKNER, OF PETERSBURG, VIRGINIA.

SPARK-GAP ATTACHMENT FOR SPARK-PLUGS.

1,398,457.

Specification of Letters Patent. Patented Nov. 29, 1921.

Application filed November 14, 1919. Serial No. 337,927.

To all whom it may concern:

Be it known that I, JAMES S. FAULKNER, a citizen of the United States, residing at Petersburg, in the county of Dinwiddie,

5 State of Virginia, have invented certain new and useful Improvements in Spark-Gap Attachments for Spark-Plugs; and I do hereby declare the following to be a full, clear, and exact description of the invention, such as will enable others skilled in the art to which it appertains to make and use the same.

This invention relates to spark plug attachments and more particularly to an attachment for providing a spark gap of which one sparking terminal is provided by the nut ordinarily employed for connecting the circuit wire with the central electrode of the spark plug.

10 The invention has for its object to provide an article that may be easily and quickly put in place and which may be both applied and adjusted by one unfamiliar with the general subject.

20 In the drawings:

Figure 1 is a perspective view showing a spark plug equipped with the present invention.

Fig. 2 is a section taken longitudinally 30 through the base member of the attachment in the plane of the spark plug and the circuit wire connecting the binding post of the attachment, with parts in elevation.

Fig. 3 is a detail perspective view of the 35 plate that is carried adjustably by the base and which constitutes one sparking terminal.

Fig. 4 is a transverse section through the base in a plane including the axis of the binding post.

40 Referring now to the drawings the present spark gap attachment comprises an insulating base 5 having a perforation 6 near one end that is designed to receive the upper end portion of the central electrode 7 of a common type of spark plug 8 and which is held securely upon the electrode, by means of the usual clamping nut 9 that is commonly employed for attaching a circuit wire.

The opposite end portion of the insulating 50 base 5 is slotted longitudinally, as shown at 10 to receive the stem of a binding post. This binding post stem comprises a threaded cylindrical body portion 11 at the base of which is a cross sectionally rectangular enlargement 12 that is fitted to slide longitudinally of the slot 10 while below this portion

12 is the annular enlargement or disk member 14 that fits slidably against the under face of the body 5. This binding post stem, which is in effect, a screw that is inverted 60 and passed upwardly through the slot 10 has disposed upon its threaded body portion 11 a plate 15 which is perforated for the purpose and one end portion of which rests upon the upper surface of the base 5, while 65 its other end portion is tapered and is offset from the base portion 5 and is directed toward the clamping nut 9 of the spark plug, hereinbefore referred to. The plate 15 is movable with the binding post screw 70 in the adjustment of the latter in the slot 10, so that its pointed extremity may be spaced from the nut 9 a distance to insure most efficient operation of the device and after adjustment, the parts are clamped securely 75 to the base 5, by means of a thumb nut 16 that is engaged with the threads of the body portion 11.

Upon the body portion 11 is engaged a jam nut 17 having a circumscribing channel 18 80 in its upper end portion to receive the usual resilient prong of a circuit wire connector, it being understood of course that when desired and circumstances dictate, the terminal may be held between the jam nut and the 85 clamping nut.

With this construction it will be noted that the application of the attachment to a spark plug requires only that the ordinary clamping nut 9 of a spark plug be removed, that 90 the base member 5 be then engaged over the sparking plug electrode, that the nut 9 be then screwed down and that the circuit wire be then connected in either manner described and the terminal plate adjusted to give the 95 required spark gap.

By reason of the downturned finger 18 of the plate 15 engaging in the slot 10, rotation of the plate is prevented, not only when the article is in use but also when the nuts of 100 the binding post are manipulated. The structure thus permits of delicate adjustment and insures positively against loosening of the parts under the influence of vibration of the engine and other extraneous influences. 105

What is claimed is:

1. A spark gap attachment for spark plugs comprising an insulating base having a perforation at one end to snugly receive a spark plug electrode and having at its 110 other end a slot extending in the direction of the perforation, a terminal plate disposed

upon the base and having at one end a finger slidably engaged with the slot and having its opposite end offset from the base and directed toward said perforation, and means engaged through the slot and the plate for clamping the plate to the base.

2. A spark gap attachment for spark plugs comprising an insulating base plate having at one end a perforation to receive the electrode of the spark plug and at its other end a longitudinal slot extending in the direction of the perforation; a screw having an angular base slidably mounted in the slot and held against rotation therein,

the screw below the base being enlarged and impinging against the under face of the base, a plate disposed upon the base and having a perforation through which the screw is fitted, the plate at one end being offset from the base and directed toward the perforation and having at its opposite end a finger slidably engaged in the slot, a clamping nut engaged upon the screw against the plate and a jam nut upon the screw and against the clamping nut.

In testimony whereof I affix my signature.

JAMES S. FAULKNER.
